SOLIDIFIED GAS CARTRIDGE OR DRUM

Harry S. Cornish, Los Angeles, Calif.

Application May 14, 1930, Serial No. 452,242

12 Claims. (Cl. 62—91.5)

This invention relates to the construction of drums or containers employed as a source of supply of CO₂ gas or other gas under pressure to be employed for any desired purpose for instance for carbonating or charging liquids with a gas or for other uses. Since the invention is particularly useful in connection with a gaseous agent like CO₂ gas, which after being reduced to solid or ice form is capable of liberating the gas or re-

10 turning to the gaseous state, the invention will be described for illustration in connection with that particular agent. It is to be understood however that the invention may be employed in connection with other gases which by suitable

15 means can be reduced to a solid or ice form.

It is common practice to employ heavy steel drums or containers for the shipment of liquid CO₂, said drums being filled with the gas under very heavy pressure as high as one thousand 20 pounds which is sufficient to liquefy practically all the gas although there is always some gas in the limited space not occupied by the liquid. Said drum charged with the liquid at any suitable plant is then shipped to the point where the gas 25 is to be employed the gas under pressure being liberated from the drum or tank through a proper outlet for carbonating liquids, particularly for soda water fountains.

In the art as heretofore practiced it is necessary to ship the heavy drum after it has become exhausted as a supply of gas back to the filling plant and then, after refilling, reship it to the place of use. The object of the present invention is to avoid the necessity of shipping the heavy 30 drum back and forth and permit the use therein of solid or compressed CO₂ ice compressed into blocks or masses said CO₂ ice being manufactured at a suitable plant and being itself shipped in cartridges of convenient sizes to the point of use 35 of the CO₂ gas and there introduced into the drum which is thereafter properly sealed. The gas liberated from said charge or load of CO₂ ice is used as the charging CO₂ gas or gas for other purposes. If solid CO₂ ice is charged into a container or drum in an amount which will practically fill the interior spaces thereof and the drum is sealed against escape of the gas there will develop in the course of time excessive and dangerous 40 internal pressures.

45 The object of my present invention is not only to avoid the necessity of shipping the heavy drum or container back and forth but to so construct the drum as to avoid the danger of charging it with such a size or bulk of ice block at the point of use that a dangerous or excessive pressure will

develop therein from the conversion of the ice into the gas and liquid.

A further object is to adjust or predetermine the relation or proportion of the size or bulk of the ice cartridge or block to the gas holding spaces or capacity of the tank, so that only the desired predetermined maximum of pressure can be developed therein after the introduction of the cartridge or block of CO₂ ice. By my invention therefore it will be seen I not only avoid 10 the expense of shipping the gas drum or container back and forth, which element of expense is large owing to the great weight of the gas drum as compared with its contents but I also automatically limit the maximum of pressures 15 which might develop and which might be of sufficient degree or amount to prohibit the use of the ice within the drum as the source of gas. The solid CO₂ gas or ice only according to the present invention is shipped, being placed if desired in 20 special cartridges or holders which at the point of use may be introduced into the drum of my invention which is thereafter sealed against leakage or escape of gas through the valve controlled outlet.

25 A further object of the invention is to so construct the drum or container as to facilitate the reloading of the drum or container with the CO₂ ice transported to the place of use, to which end the invention consists in providing said drum or 30 container with a removable insert adapted to hold or support a block or cartridge of the CO₂ ice of the predetermined or desired amount.

Another object of my invention is to provide 35 a suitable cap, head or seal for the drum which may be easily removed for insertion of the ice block or cartridge and then replaced and locked and which at the same time is of such construction as to permit the utilization of the ordinary metallic drum for holding CO₂ in liquid form as 40 the drum or container of the present invention.

The present invention provides an apparatus for accurately measuring variable quantities of carbon dioxide ice which it is desired to introduce into a carbon dioxide receiving drum and where- 45 in pressures will develop due to the expansion of the gases and from which the gas is used in any useful manner.

It has always been considered essential in shipping liquid carbon dioxide in drums to limit 50 the quantity of liquid carbon dioxide contained in the drum, the theory being that the greater the quantity of gas the greater the pressure developed. This theory is undoubtedly true in that after the carbon dioxide reaches temperatures 55

over the critical temperature, that is 31.35° C. (88.43° F.), the pressure depends upon the quantity of carbon dioxide within the drum. This statement is clearly true since by releasing a portion of the CO₂ gas the pressure will decrease. Since any drum of CO₂ gas in use is likely to reach temperatures over the critical temperature it is the applicant's purpose to limit the maximum quantity of CO₂ ice which may be introduced into the drum.

By the use of this feature of the invention the following results will be attained:

(1) Such quantity of CO₂ gas will be present that for any normal temperature to which the drum is subjected the maximum pressure developed will not exceed the tabulation stated on the scale, that is, will not exceed the intended pressure.

(2) When the CO₂ ice melts into a liquid like ice water there will be no possibility be a greater quantity of liquid than can be contained in the interior of the drum.

As respects result (1) above, this point is fully explained in the statement already made. As to result (2), attention is called to the fact that CO₂ ice when converted to liquid form occupies a greater volume in the liquid form than in the ice form, where the ice is highly compressed as it is intended to be in the application. It is accordingly necessary to limit the quantity of ice so that the liquid by no chance will exceed or even approach the volume of the drum.

In the accompanying drawings:

Fig. 1 is a vertical longitudinal section through a drum or container having an internal construction embodying one form of my invention.

Fig. 2 is a side elevation of the removable cap plug or head.

Fig. 3 shows in side elevation a form of support that may be employed in connection with the drum for holding the same at one end against rolling when the same is laid down for the purpose of reapplying the cap or plug in the end after loading with the block of CO₂.

Fig. 4 is an end elevation of the drum in supported position.

Fig. 5 is a vertical section through a drum having a modification of the interior construction whereby the object of my invention may be attained.

Fig. 6 shows the ice cartridge holding portion within the drum as equipped with a suitable scale of gas pressures.

Referring to Fig. 1, I indicate the body of the ordinary container or drum for liquid CO₂ at 1. The ordinary liquid holding drum of commerce has, as well understood, a rounded end integral with the sides to form a continuous wall for the liquid holding container and at the opposite end or top an outlet for the gas indicated at 2 said outlet pipe or section 2 being equipped with suitable shut-off valves and gauges and with means for attachment to a pipe by which the gas is led to the point of use. To utilize said drum for the purposes of my invention I cut off the end of the same and provide a cap 3 adapted to be attached to and removed from the open end and to seat itself against the edge of the open end, a suitable sealing gasket being provided at the point of engagement as indicated at 4. A projection from the cap indicated at 5 enters the open end and is threaded upon its exterior for engagement with a thread on the interior of the body 1. This screw arrangement provides a means for attaching and detaching the cap by

screwing and unscrewing the same into the open end. To insure a gas tight connection at the open end I may construct the projection 5 at its end with a thin or tapered edge as indicated at 6 which may be expanded against the inner wall of the cylinder body 1 to insure a good seal. This soft or expandable end 6 is caused to engage said inner wall by the use of a tapered block 7 also tapered as shown to act as an expanding device when it is drawn down towards the end of the drum by means of a screw 8 inserted into the body of the block 7 as shown and adapted to be operated by the nut 9 countersunk in the end of the cap 3 and operable by a suitable wrench. For convenience of operation of the screw 8 and the screw threaded cap after the cylinder 1 has been loaded a holder or support 10 such as indicated in Fig. 3 may be employed said holder having feet 10' adapted to rest on the floor or table and being also provided with a hole 11 in which a boss 12 on the exterior of the cylinder 1 may fit as shown in Fig. 4. When the drum is placed upon its side with the pin 12 engaged in the opening 11 of the holder 10 the drum will be held from turning under the force applied by means of suitable tools to screw or unscrew the cap from the cylinder or to operate the block 7 for the purpose of completing the seal or relieving the seal at 6 when it is desired to remove the cap. The resistance to the turning movement is effected by the feet 10' which extend out from the frame or stirrup 10 as shown in Fig. 4.

Within the drum or container 1 is a suitable cartridge holder or support 13 for the block of solid CO₂ ice. Said holder, which for convenience I term an insert, may be in the form of a drum or cylinder equipped on its inside with a shelf or support 14 made adjustable if desired within the cylinder 13 and adapted to be clamped in any desired position by the clamping devices 15 which pass through flanges of the shelf 14 and may be in the form of screws as indicated that may be operated to free the shelf 14 or to clamp it in position when it is desired to change the position of the shelf. The cylinder or holder 13 may be adapted to be inserted from the bottom of the cylinder 1 and may be furnished with a flange 13' that engages a shoulder on the inside of the drum 1 when the cylinder 13 is pushed upwardly. This device limits the movement and depth of insertion of the cylinder 13 when the same is inserted and held by engagement of the device 7 therewith. The position of the shelf or support 14 for different sizes of CO₂ ice block or cartridge to be loaded into the drum may be accurately determined by the use of a scale 17 applied to the side of the cylinder 13 and contiguous preferably to an open slot therein through which the edge of the table or shelf 14 may be viewed. With the construction illustrated it is assumed that the cartridge of ice when supported on the shelf will reach to the top of the drum 13 and practically no higher. In other words the amount of CO₂ ice loaded into the drum is of such size as to fill the same from the shelf or support to the top edge thereof. If the shelf is at its lowermost position the size of the block of ice as compared with the space into which the gas developed therefrom may expand is proportionately the greatest.

The cartridge of CO₂ ice, which it is desired to use in a given container or drum 1 equipped in the manner described, may have the pressure which will develop under any maximum normal temperature stamped or marked on the side of the paper or other envelope of the cartridge of

ice, while the movable shelf for support 14 will determine the amount or size of cartridge that can be used therein for the desired maximum interior pressure. This support can be set for 5 this position and left that way where the same quantity of ice or pressure is always to be used or can be changed when it is desired to use the device for different maximum pressures and consequently other sizes of cartridges. This is 10 an especially desirable feature if the invention be employed for ice formed from other gases than CO₂ gas. Tests will positively indicate the position that the shelf or support 14 should have for a given inside diameter and length of gas holding drum. As will be understood, for uniformity of results the density of the ice in manufacturing the same should be made uniform so that it will be definitely known how much space should be left for the gas to expand into in 15 order to control the maximum interior pressure under any normal maximum temperatures. In practice the holder for the ice constructed as described and adjusted for the desired size of block and pressure, and which may be termed the insert, would be employed, simply by slipping the block of ice shipped in a paper wrapper, for instance, into the insert, with or without the wrapper but preferably without and then placing the insert with its load of ice into the drum and 20 sealing said drum by the device described. Ordinarily the insert provided with the scale and movable shelf would remain as part of the drum equipment, with the user or customer and so far as said customer is concerned the insert shelf 25 would remain in position for renewals of the ice.

The device is primarily intended for deliveries of the manufactured ice within short ranges such as in a city but the ice cartridges can be shipped in carload lots and be used for delivery locally. 40 In practice it is desirable to manufacture the cartridges from ice pressed into different lengths of rods at the manufacturing ice plant or long rods may be made and cut to the desired lengths said lengths of cartridge being preferably of the desired cross-sectional dimension to fit the containers or shells 13.

Assuming that an ice cartridge is placed in the insert 13 and is of such size as to fill the space in the insert from the 850 mark on the scale to the 45 top of the shell or insert this would result in the development of a maximum pressure of gas for the assumed maximum temperature of say 850 pounds, that pressure being secured by the proportioning of the size of cartridge with the standard density of ice, to the cubic contents of the remaining spaces in the drum or holder into which the gas released from the ice may expand, this comparatively low pressure being due to the fact that a comparatively large space for expanding 50 the gas is left. If, however, the shelf be lowered and a larger cartridge filling the insert is placed in the drum the expanding gas holding space being then comparatively smaller the maximum developed pressure will be higher. Obviously by 55 restricting the size of the cartridge or the relation or proportion of its size or bulk to the gas holding spaces or capacity of the tank the developed pressure will be less and by this means unsafe pressure may be avoided while at the same 60 time all the advantages of shipping the ice in cartridges for use in properly constructed tanks are secured.

While I have described the invention as carried out by the shipping of cartridges of ice to be inserted into shells or inserts of restricted or pre-

determined capacity as ice holders it would be possible to ship the ice in a shell or insert for use in a construction of container such as illustrated in Figs. 5 and 6.

In Fig. 5 the insert is a long tube or shell 18 which as shown extends from the outlet end of the container 1 to the bottom or base thereof. Said insert might be loaded at the ice making plant and shipped for insertion into the holder 1. In this case the capacity of the shell or insert as 10 related to the gas holding capacity or gas collecting space of the container could be predetermined by the diameter of the tube or insert which could be loaded to different heights according to the limit of pressure desired. In this instance the 15 shell or insert would be provided with suitable gas outlets near its upper end as shown. The loading of the insert to its full length with the ice cylinder or pencil would of course result in the production of the maximum permissible pressure in the 20 particular holder 1 with which it is used. An insert of larger diameter as indicated in Fig. 6 but of less length than the cylinder might of course be employed and the loading thereof to different heights would result in the production 25 of different maximum internal pressures as indicated by the scale on the side of the shell or insert. The pressures indicated are shown merely for the sake of example but in practice would of course be lower than those shown in Fig. 6. 30 The shell or insert may be held after insertion as indicated in Fig. 5 by a boss projecting from the cap and entering one end of the tube and by engagement of the opposite end with a socket in said latter end as shown. Other means of 35 course might be employed for holding the insert in place. In Fig. 6 the insert is preferably closed at its lower end and is supported in a sleeve or ring projecting from the base of the drum. In this figure the seal is effected by engagement of 40 the end of the cap or plug with a gasket on a shoulder within the end of the drum or container.

What I claim is:

1. A device for producing carbon dioxide under 45 pressure from solidified carbon dioxide, comprising a container, and a compartment in the container to hold solidified carbon dioxide, the volume of the compartment not exceeding 40% of the volume of the container to limit the amount 50 of solidified carbon dioxide which can be introduced into the container at one time.

2. A device for producing carbon dioxide under 55 pressure from solidified carbon dioxide, comprising a container, and means in the container to prevent the introduction into the container at one time of a volume of solidified carbon dioxide exceeding 40% of the volume of the container.

3. A tank or container adapted to collect and 60 retain a gas under heavy pressure and containing means for supporting CO₂ in ice form and means in said container for gauging the bulk of the ice inserted with relation to the size of the gas containing spaces in said container to limit the accumulated maximum pressure to be derived from 65 said ice to the desired degree.

4. A hermetically sealed container for CO₂ ice adapted to receive a mass of the ice of and having means in said container for predetermining the 70 size or cubic content of the inserted mass predetermined with relation to the volume of hermetically sealed pressure proof gas spaces in which a gas liberated from the ice in the cooling operation may collect and may be confined thereby 75

- predetermining the extent of possible maximum accumulated gas pressure.
5. A sealed receptacle or container adapted to hold a block of inserted CO₂ ice in combination with means in said container for gauging the size of the inserted and contained block of ice as compared with the cubic gas capacity of the spaces into which the gas may expand and be retained, thereby predetermining the ultimate maximum 10 pressure of gas developed.
6. A sealed container provided with a suitable gas retaining space for the gas liberated from a loading of gas generating ice inserted within the same and means in said container for adjusting 15 the size of the load of ice to limit the developed pressure to the desired maximum pressure in the container.
7. A hermetically sealed container for a solid mass of ice formed from a gas and provided with 20 a removable insert having means for supporting the desired size of ice mass suitable for reloading the container to produce the predetermined maximum pressure of gas within the same on the attainment of a selected temperature.
- 25 8. In a device of the character described, a removable insert for gas developing, said insert being provided with a gauge indicating the maximum pressure of gas that will be developed in the container for a determinate size of ice cartridge 30 loaded into the same by means of the insert.
9. A gas pressure retaining container for CO₂ ice consisting of a drum provided with a removable end and with an insert having means for holding a predetermined load of ice to be loaded into the container after being placed in said insert.
10. In a container for a body of ice adapted to liberate a gas, a removable head and an insert having means for holding the desired charge of ice for reloading into the container, said insert 10 being insertable through the opening closed by the head and means for securing the head in position to close the gas spaces of the container with a gas tight joint.
11. A container for carbon dioxide ice comprising 15 a pressure retaining drum, a removable ice supporting insert for said drum, means for sealing said drum with said insert inserted within the same and means for adjustably regulating the amount of carbon dioxide ice carried by said insert.
12. A device for producing carbon dioxide gas of the desired pressure from solidified carbon dioxide comprising a container and a retaining device therein having adjustable means to receive 25 the solidified carbon dioxide and to definitely limit the amount of solid material to an amount such that on the application of heat the pressure generated will be of the desired degree.

HARRY S. CORNISH. 30
